SWITCH ACTUATING MECHANISM

Malcolm E. Henning, Des Moines, Iowa, assignor
to Penn Electric Switch Co., Des Moines, Iowa,
a corporation of Iowa

Original application November 30, 1931, Serial No.
577,906, now Patent No. 1,962,506, dated June
12, 1934. Divided and this application March
12, 1934, Serial No. 715,125

13 Claims. (Cl. 200—138)

The object of my invention is to provide a switch actuating mechanism which is simple, durable and comparatively inexpensive to manufacture, the present application being a division 5 from my co-pending application Serial No. 577,906, filed November 30, 1931, now Patent No. 1,962,506, June 12, 1934.

A further object is to provide a switch structure in which one switch or circuit breaker is actuated immediately upon movement of a power mechanism in one direction, the power mechanism having a lost motion connection with the switch or circuit breaker and means being provided to cause the connection to shift to its opposite limit of movement upon further movement 10 of the power mechanism before the mechanism operates further to close another switch, thus causing immediate operation of the first switch or circuit breaker and delayed closing of the second one.

A further object is to provide a novel form of lost motion connection to increase the time period occurring between the opening of the first switch or circuit breaker and the closing of the second switch by the power mechanism.

Still another object is to provide a lost motion connection of this character comprising a pin, a slot and resilient means, the slot having recessed ends and the resilient means tending to retain the pin in either of the recesses whenever it registers therewith, yet operable to permit the pin to slip out of one recess, travel the length of the slot and enter the other one upon added pressure being exerted sufficient to overcome the tension of the spring.

With these and other objects in view my invention consists in the construction, arrangement and combination of the various parts of my device, whereby the objects contemplated are attained, as hereinafter more fully set forth, pointed out in my claims and illustrated in the accompanying drawing, in which:

Figure 1 is a front elevation of the switch structure embodying my invention and showing the cover plate for the switch casing removed.

Figure 2 is a partial view of Figure 1 showing elements thereof in a different position.

Figure 3 is a view of a part of Figure 2 showing the parts in still another position; and

Figure 4 is a sectional view on the line 4—4 of Figure 1.

On the accompanying drawing I have used the reference numeral 10 to indicate a switch casing. A hub 12 extends therefrom in which a shaft 14 is journaled. The outer end of the shaft has

secured to it one end of a bimetal temperature responsive element 16, the other end of which is secured to the hub 12.

The switch structure illustrated is designed for use as a "stack switch" for controlling a fuel burner. The hub 12 is extended through the wall of a chimney or the like so that the bimetal element 16 projects into the chimney and is thus responsive to stack temperatures therein. Upon a change of temperature, the element 16 either 10 winds or unwinds and in so doing rotates a disc 18. The disc 18 is frictionally engaged with a freely rotatable disc 20, the friction being provided by a spring 22 and a washer 24 interposed between the spring and the disc 20. The disc 15 20 has an arm 26 to which is pivoted the upper end of a link 28. The lower end of the link 28 terminates in a pin 30 designed to travel in a slot 32 of an actuating element 34. The pin 30 has its terminal end bent as indicated at 36 to retain it in the slot.

The actuating element 34 is pivoted on the pin 38. The ends of the slot 32 are recessed as indicated at 40 and 42. A spring 44 is connected with the pins 30 and 38 for constraining the pin 30 to 25 remain in either the recess 40 or the recess 42 when it registers therewith, yet the pin 30 can slip out of one recess and travel the length of the slot, then drop into the other recess when sufficient pressure is exerted to overcome the 30 tension of the spring.

The actuating element 34 carries a contact 46 adapted to cooperate with a contact 48. The lower end of the actuating element 34 is provided with a finger 50 adapted to actuate a sliding bar 35 52 to move a leaf spring 64 and thereby contact 54 carried by it with respect to a contact 56. The contacts 46, 48, 54 and 56 may be, on the type of switch shown, included in the circuit of an oil burner or the like as shown in my co-pending application, referred to in the first object of this application, or may be included in any other circuit to which they are adaptable.

The finger 50 is adapted to coact with the left 45 end of the sliding bar 52. The bar slides through a bracket 58 and has an inclined portion 60 to slide along a flange 61 and thereby raise the left end of the bar as it slides from the position of Figure 1 to the positions of Figures 2 and 3 successively. By the time that the Figure 3 position is reached a corner 62 of the bar 52 has been raised above the finger 50 so that the finger, upon further movement, can slip under this corner without causing further movement of the 55

bar and the bar 52 is then free to be returned toward the left by the leaf spring 64.

The right end of the bar 52 is adapted to engage the leaf spring 64 on which the contact 54 is mounted. When it swings the spring 64 toward a somewhat stiffer spring 66 it separates the contacts 54 and 56 and upon the spring 64 engaging the spring 66, more resistance is encountered by the bar 52 so that the slight resistance of the light spring 64 will permit the pin 30 to remain in one of the recesses of the slot 32 while separating the contacts 54 and 56, but the pin will shift to its opposite limit of movement upon further movement of the link 28 due to the increased resistance of the spring 66. Thereafter when the position of Figure 3 is assumed the bar 52 will be returned toward the left by the springs 66 and 64 and the contacts 54 and 56 will be reclosed.

20   Practical operation

In the operation of my switch structure, assuming the parts to be in the position of Figure 1, a winding up movement of the bimetal element 16 will cause downward movement of the link 28. This will cause immediate opening of the contacts 46 and 48 and as soon as they are open their full limit or the actuating element 34 strikes the switch casing 10, additional downward movement of the element 28 will cause the pin 30 to slip out of the recess 42 and travel downwardly through the slot 32, the friction connection between the shaft 14 and the link 28, of course, being of sufficient value to overcome the tension of the spring 44.

When the power element 16 twists in an unwinding direction, however, a more complex sequence of events occurs. First the finger 50 will engage the corner 62 of the sliding bar 52 as in Figure 2, as soon as the link 28 moves upwardly. This will slide the bar to open the contacts 54 and 56 as shown, against the slight tension of the light spring 64.

After the position of Figure 2 is assumed, the spring 66 opposes travel of the bar 52, thus causing the pin 30 to slip out of the recess 40 upon further upward movement of the link 28. The pin 30 then travels upwardly through the slot 32 and finally comes to rest in the recess 42. Further upward movement of the link 28 causes the bar 52 to slide toward the right in opposition to the spring 66 until the position of Figure 3 is reached, where the left end of the bar 52 has been raised sufficiently by the incline 60 to cause the corner 62 to override the finger 50. The springs 66 and 64 then open the contacts 54 and 56 and further upward movement of the link 28 swings the actuating element 34 from the position of Figure 3 to the position of Figure 1 thus closing the contacts 46 and 48.

In the circuit described in my co-pending application, the contacts 54 and 56 are included in a relay circuit while the contacts 46 and 48 are included in an ignition circuit. Thus the relay contacts 46 and 48 are opened so that the circuit is broken through the relay for stopping the operation of the burner and a purging period is provided between such opening and the re-establishment of the ignition through the contacts 46 and 48 by the particular type of lost motion connection provided.

This is just one example of an installation in which this type of switch structure and lost motion connection can be used, as the lost motion connection can be used in any switch structure where found applicable.

An adjusting screw 68 is provided for varying the tension of the springs 64 and 66, in accordance with the requirements of the spring 44 and other factors.

Some changes may be made in the construction and arrangement of the parts of my device without departing from the real spirit and purpose of my invention, and it is my intention to cover by my claims, any modified forms of structure or use of mechanical equivalents, which may be reasonably included within their scope.

I claim as my invention:

1. In a switch structure, a pair of switches, an actuating element therefor, power mechanism for moving said actuating element, said power mechanism having a lost motion connection with said actuating element, means constraining said lost motion connection to remain at either limit of its lost motion, said actuating element being connected with one of said switches to open it when said power mechanism moves in one direction, means opposing the actuating element to cause said lost motion connection to shift to its other limit upon further movement of the power mechanism and trip means for permitting said switch to move to closed position upon movement of said power mechanism after said lost motion connection has so shifted and the other switch being connected with said actuating element to be closed thereby after the first switch has been so closed.

2. In a switch structure, a pair of switches, an actuating element therefor, power mechanism for moving said actuating element, said power mechanism having a lost motion connection with said actuating element, means constraining said lost motion connection to remain at either limit of its lost motion, said actuating element being connected with one of said switches to open it when said power mechanism moves in one direction, means opposing the actuating element to cause said lost motion connection to shift to its other limit upon further movement of the power mechanism and trip means for permitting said switch to move to closed position upon movement of said power mechanism after said lost motion connection has so shifted, the other switch being connected with said actuating element to be closed thereby after the first switch has been so closed and to be opened upon movement of the power mechanism in an opposite direction, movement of the second switch to open position being limited whereby said lost motion connection again shifts to its original limit of movement after such opening of said second switch.

3. In a switch structure, a pair of switches, an actuating element therefor, power mechanism for moving said actuating element, said power mechanism having a lost motion connection with said actuating element, means constraining said lost motion connection to retain either limit of its lost motion, said actuating element being connected with one of said switches to change its position when said power mechanism moves in one direction, means opposing the actuating element to cause said lost motion connection to shift to its other limit upon further movement of the power mechanism and trip means for permitting said switch to move to its other position upon movement of said power mechanism after said lost motion connection has so shifted and the other switch being connected with said actuating element for having its position changed thereby after the first switch has been moved to its other position.

4. In a switch structure, a pair of switches, an actuating element therefor, power mechanism for moving said actuating element, said power mechanism having a lost motion connection with said actuating element, means constraining said lost motion connection to retain either limit of its lost motion, said actuating element being connected with one of said switches to change its position when said power mechanism moves in one direction, means opposing the actuating element to cause said lost motion connection to shift to its other limit upon further movement of the power mechanism and the other switch being connected with said actuating element to be moved to one of its positions thereby after the first switch has been moved to its other position.
5. In a switch structure, a pair of switches, an actuating element therefor, power mechanism for moving said actuating element, said power mechanism having a lost motion connection with said actuating element, means constraining said lost motion connection to retain either limit of its lost motion, said actuating element being connected with one of said switches to change its position when said power mechanism moves in one direction, means opposing the actuating element to cause said lost motion connection to shift to its other limit upon further movement of the power mechanism and the other switch being connected with said actuating element to be moved to one of its positions thereby after the first switch has been moved to its other position.
6. In a switch structure, a pair of switches, an actuating element therefor, power mechanism for moving said actuating element, said power mechanism having a lost motion connection with said actuating element, means constraining said lost motion connection to retain either limit of its lost motion, said actuating element being connected with one of said switches to change its position when said power mechanism moves in one direction, means opposing the actuating element to cause said lost motion connection to shift to its other limit upon further movement of the power mechanism and the other switch being connected with said actuating element to be moved to one of its positions thereby after the first switch has been moved to its other position, movement of the second switch to its other position being limited whereby said lost motion connection again shifts to its original limit of movement after such movement of said second switch.
7. In a switch structure, a pair of switches, an actuating element, power mechanism for moving said actuating element, the connection between said power mechanism and said actuating element comprising a slot having recessed ends and a pin and resilient means constraining said pin to remain in the recessed ends of said slot, although movable therefrom upon the application of pressure sufficient to overcome the tension of said spring, said actuating element being connected with one of said switches to open it when said power mechanism moves in one direction, means opposing the actuating element to cause said lost motion connection to shift to its other limit upon further movement of the power mechanism.

anism and trip means for permitting said switch to move to closed position upon movement of said power mechanism after said lost motion connection has so shifted and the other switch being connected with said actuating element to be closed thereby after the first switch has been so closed. 5

8. In a switch structure, a pair of switches, an actuating element, power mechanism for moving said actuating element, the connection between said power mechanism and said actuating element comprising a slot having recessed ends and a pin and resilient means constraining said pin to remain in the recessed ends of said slot, although movable therefrom upon the application 10 of pressure sufficient to overcome the tension of said spring, said actuating element being connected with one of said switches to open it when said power mechanism moves in one direction, means opposing the actuating element to cause 15 said lost motion connection to shift to its other limit upon further movement of the power mechanism and trip means for permitting said switch to move to closed position upon movement of said power mechanism after said lost motion 20 connection has so shifted, the other switch being connected with said actuating element to be closed thereby after the first switch has been so closed and to be opened upon movement of the power mechanism in an opposite direction, movement 25 of the second switch to open position being limited whereby said lost motion connection again shifts to its original limit of movement after such opening of said second switch.

9. In a switch structure, a pair of switches, an actuating element, power mechanism for moving said actuating element, the connection between said power mechanism and said actuating element comprising a slot having recessed ends and a pin and resilient means constraining said 30 pin to remain in the recessed ends of said slot, although movable therefrom upon the application of pressure sufficient to overcome the tension of said spring, said actuating element being connected with one of said switches to change its 35 position when said power mechanism moves in one direction, means opposing the actuating element to cause said lost motion connection to shift to its other limit upon further movement of the power mechanism and trip means for permitting 40 said switch to move to its other position upon movement of said power mechanism after said lost motion connection has so shifted and the other switch being connected with said actuating element to have its position changed thereby 45 after the first switch has been moved to its other position.

10. In a switch structure, a pair of switches, an actuating element, power mechanism for moving said actuating element, the connection between said power mechanism and said actuating element comprising a slot having recessed ends and a pin and resilient means constraining said pin to remain in the recessed ends of said slot, although movable therefrom upon the application 50 of pressure sufficient to overcome the tension of said spring, said actuating element being connected with one of said switches to change its position when said power mechanism moves in one direction, means opposing the actuating element to cause said lost motion connection to shift to its other limit upon further movement of the power mechanism and the other switch being connected with said actuating element to be moved to one of its positions thereby 55

after the first switch has been moved to its other position.

11. In a switch structure, a pair of contacts, power mechanism for actuating said contacts, 5 an actuating element interposed between said power mechanism and said contacts, said actuating mechanism including a lost motion connection and means constraining said lost motion connection to remain at either limit of its lost motion, said actuating element being cooperable with said contacts to open the same upon initial movement of the power mechanism and actuating element and means to cause said lost motion connection to shift to its opposite position and said contacts to return to their initial position upon further movement of said power mechanism.
12. In a switch structure, a pair of contacts, power mechanism for actuating said contacts, 20 an actuating element interposed between said power mechanism and said contacts, said actuating mechanism being connected with said power mechanism by a pin and slot connection, the ends of said slot being recessed, resilient

means constraining said pin to remain in either of said recesses when it registers therewith, said actuating element being cooperable with said contacts to open the same upon initial movement of the power mechanism and actuating element 5 and means to cause said pin and slot connection to shift to its opposite position and said contacts to return to their initial position upon further movement of said power mechanism.

13. In a switch structure, the combination of 10 power mechanism and contacts with a lost motion connection therebetween, means to constrain said lost motion to remain at either limit of its lost motion and means to cause said lost motion connection to shift to its opposite position after initially moving said contacts, said means comprising a spring with which the connection engages after initially moving said contacts and which is of sufficient tension to overcome the constraint of said means for constraining the lost motion connection to remain at either limit of its lost motion.

MALCOLM E. HENNING.
